UNITED STATES PATENT OFFICE.

GEORGE G. FLOYD, OF CHICAGO, ILLINOIS, ASSIGNOR TO AMERICAN STEEL FOUNDRIES, OF CHICAGO, ILLINOIS, A CORPORATION OF NEW JERSEY.

EMERGENCY DRAFT GEAR FOR RAILWAY CARS.

Application filed December 31, 1917. Serial No. 209,622.

To all whom it may concern:

Be it known that I, GEORGE G. FLOYD, a citizen of the United States, and resident of Chicago, in the county of Cook and State 5 of Illinois, have invented certain new and useful Improvements in Emergency Draft Gears for Railway Cars, of which the following is a specification.

This invention relates to emergency draft 10 gears for railway cars.

One of the objects of the invention is to provide a universal emergency draft gear applicable to cars, the dimensions of which between the various associated parts differ 15 widely.

Another object is to provide an emergency draft gear which may be assembled readily in place in a minimum amount of time with an expenditure of a minimum amount of 20 effort.

Another object is to provide a novel emergency draft gear capable of being attached to a damaged car to place the same in regular train line service.

25 A further object is to provide an emergency draft gear adapted to meet the various requirements for successful commercial operation.

Generally speaking, these and other objects are accomplished by providing an emergency draft gear comprising a plurality of articulated parts, all of which are relatively light and are arranged to be adjusted and otherwise cooperate with various parts 35 of the car.

The invention is illustrated on the accompanying sheets of drawings, in which—

Figure 1 is a fragmentary sectional view 40 of a freight car equipped with my improved emergency draft gear and showing the same in side elevation;

Figure 2 is a plan view of my improved draft gear;

Figure 3 is a top plan view, and Figure 45 4 a side elevation of the supporting arm of my emergency draft gear;

Figure 5 is an enlarged detail sectional view taken in the plane of line 5—5 of Figure 1;

50 Figure 6 is a detail side elevation of the adjustment bar; and,

Figure 7 is a top plan view, Figure 8 a front elevation, and Figure 9 a side elevation 55 of the spring cap or seat associated with the adjustment bar.

The various novel features of my invention will be apparent from the following description and drawings and will be particularly pointed out in the appended claims.

Draw bars very frequently are jerked out 60 of operative association with the remaining portions of the draft gear as a result of extreme pulling strains. As a matter of fact, it is not an uncommon occurrence to have the draw bar, yoke and draft gear, the end 65 of the car, or all combined, pulled out. Under such conditions it is necessary to repair the car either temporarily or permanently, in order that the same may be placed in a train for regular train line service. It is 70 the plan of railroads as now operated to make an emergency repair at the nearest repair shop as cheaply and as quickly as possible so that the car can be forwarded in regular train service to the next largest 75 repair shop; but to put this car in train service it must have, for one thing, a regular operative coupler of some sort that can be coupled and uncoupled from the side of the car in the regular manner. If the repair is 80 made by the use of an emergency draft gear of any kind it must be able to stand the buffing and pulling shocks of the regular train in the regular way. Therefore, an emergency repair to a damaged coupler or draft 85 gear must be such that it will stand regular train line service to its destination. If the car is loaded for points beyond destination of the road on which the accident occurs, there are two plans in making repairs that 90

can be followed. One is an emergency repair sufficient to get the car to a repair shop when the load is transferred to another car, or the repair may be made of sufficient permanency that the car may proceed to its foreign destination. In these days of heavy engines and heavy tonnage trains, many times the end sill of the car, and the entire end also, comes off with the draft gear when the latter is pulled out, leaving nothing but 95 the protruding ends of the foundation sills of the car. This is especially true of wooden cars.

All freight car wheels are 33" in diameter, and consequently the distance from the top 105 of the track to the top of the axle at the middle thereof is a standard dimension. Heretofore it has been proposed to use the center of the axle between the two wheels as a rest for an emergency draft gear. As it is 110

necessary to have the distance from the top of the track to the center of the coupling a standard distance of $34\frac{1}{2}$ ", it is very easy, looking at the matter from one angle, to maintain this distance of $34\frac{1}{2}$ " to the center of the coupling in the emergency draft gear by resting the device upon the top of the axle nearest the end of the car. Extending to the rearward end of the arrangements heretofore known is a bar with several holes of sufficient diameter to take an ordinary king pin with which the car is equipped, the idea being to raise the body off the car trucks, put the rear end of the bar in between the two center plates, lower the car again so that the king bolt will enter one of the various holes at the back of the bar, thereby anchoring the draw bar as a whole to the car and the truck. It is an unusual thing for the trucks to be damaged in ordinary cases where the draw bar, the draft gear, the end sill or all are pulled out. Therefore, for all practical purposes the trucks are left intact and in full operating condition.

While the arrangements heretofore known are of value, the same can be improved upon. It will be noted that the earlier arrangement is a solid structure and therefore not capable of being applied to cars having varying heights of truck bolster center plates from the track, and also cars which vary greatly in distance from the center of the king bolt to the forward end. Also such earlier arrangement makes no provision for any vertical movement of the truck itself, which is occasioned from the oscillation of the car in running. Another point to be borne in mind in connection with emergency draft gears is that at best these draft gears as a whole are relatively heavy and almost impossible for two or three men to handle without special equipment, which they very seldom have for repair work of this nature. Therefore, I have improved emergency draft gears so that the same may be of universal application, that is, to cars the dimensions of the associated portions of which vary widely, and at the same time I have provided an emergency draft gear which is built up of a plurality of articulated parts, no one of which is excessively heavy and all of which may be readily handled by one or two men, even when working under adverse conditions under a car.

It is found that the distance from the top of the track to the truck bolster center plate bearing, as indicated by A, varies a total of 9" in different cars. The distance from the center of the king bolt to the forward end of the car, as indicated by B, varies 2' 3", this variance being found as a result of canvassing cars built by different railroads. Also the distance from the center of the axle to the center of the other one on the same

truck, as indicated by C, varies 14", or the total distance from the center of the king bolt to the center of the forward axle on which it is proposed to rest this emergency draft gear, varies 7" in different cars. The distance from the top of the track to the center of the axle is $16\frac{1}{2}$ ", and while there is a variation in the diameter of the axle for the different classes of cars, this variation is for all practical purposes of no moment, as it is so small. The distance from the top of the track to the center of the coupling is $34\frac{1}{2}$ ", which is a universal standard. It is seen, therefore, that the center of the coupler is located at a constant height from the track, and also that the distance to the top of the axle is a constant height, but there is a variation of 9" in the height of the center plates to which the rear end of the emergency draft gear is to be anchored. It is also necessary to vary the length of the entire emergency draft gear in accordance with the individual dimensions of the car involved from the center of the king bolt to the face of the end sill of the car or of the striking block.

Let it be assumed that the axle is equidistant from the king bolt to the center of the coupling. Therefore, a 9" variation in the height of the center plate at the king bolt would mean a variation of half this amount at the axle which supports the draft gear.

Referring particularly to the figures of the drawing, it will be noted that I have provided an emergency draft gear, including a center beam 10, the rear end of which is pivotally connected by a pin 11 to a connecting plate 12 which rests in a horizontal position between the two center plates 13 and 14. It is apparent from the remarks made hereinabove that it is necessary to have a pivotal connection between the center beam 10 and the connecting plate 12 if the coupler is to remain at a constant height for varying conditions. To take up this vertical movement at the axle which supports the entire emergency draft gear, I have provided an adjustable supporting arm 15, the front end of which is pivotally connected to the center beam 10 by means of a pin 30, and the rear end of which takes the form of a horizontal bar 16 having a wearing plate 17 connected thereto, which rests upon the front axle 18 of the truck. The adjustable supporting arm 15, intermediate its ends, is connected to the center beam 10 by an adjustment bar 19, (see Figs. 1, 5 and 6) the lower end of which is provided with a plurality of openings 20 which may be brought into register with any one of the openings 21 in the supporting arm 15, a pin 22 being provided for passing through the registering openings for effecting a pivotal connection between the supporting arm 15 and supporting bar 19. The upper end of the support-

ing bar 19 is provided with an elongated opening 23 for the reception of a pin 24 carried by the center beam 10. The center beam 10 and coupler are yieldably supported by a spring 25, the lower end of which rests upon a seat 26 which is held in a given position by the shoulders 27 of the supporting bar 19. The top of the spring 25 is engaged by a cap which is a duplicate of the 10 seat 26 shown in Figures 7, 8 and 9, the spring being initially compressed a given amount by forcing the spring cap downwardly to a point where the collar segments 28 extend below the shoulders 29 of 15 the supporting bar 19, whereupon the spring cap 26 may be given a quarter turn to lock the spring 25 in its compressed condition. It is apparent, therefore, that the coupler and center beam may oscillate vertically in 20 accordance with operating conditions of the car when the car or train is in motion. By providing the supporting arm 15 and the adjustable bar 19 with the openings 21 and 20, respectively, the forward end of the 25 coupler may be raised to the proper height after the connecting plate 12 is placed in position between the two center plates 13 and 14, the pin 22 then being inserted in the proper openings for connecting the supporting arm and bar to hold the front end of the coupler in adjusted position.

The variation in the distance from the king bolt 31 to the end of the car is taken care of by providing a series of holes 32, 35 any one of which may receive the king bolt 31.

Instead of casting the coupler head 33 integral with the center beam 10, the latter is provided with a square pocket 34 in its 40 outer end, into which is fitted a short shank 35 of the coupler, the shank being secured in the pocket by a plurality of bolts 36 passing through corresponding openings in the walls of the pocket through the shank.

45 In repairing a car disabled in the manner above described, the emergency draft gear is applied in the following manner: The connecting plate 12, which is a comparatively light piece, is placed between the center 50 plates 13 and 14 and locked in position by the king bolt 31 which passes through any one of the openings 32 in the connecting plate in accordance with the dimensions of the car. After this piece is in place, the 55 center beam 10 is pivotally connected to the connecting plate 12 by the pin 11. The coupler head is connected to the front end of the center beam 10 by passing the bolts 36 down through the openings in the housing of the pocket and through the openings in the coupler shank, the center beam being supported at the proper height in any suitable manner. The supporting arm 15 is then pivotally connected to the center beam 60 10 by the pin 30. The adjustment bar 19

may be pivotally connected to the supporting arm at the time the latter is connected to the center beam 10 and the adjustment bar pivotally connected to the center beam by the pin 24. In view of the fact that the 70 shank of the coupler used in this emergency draft gear is relatively short, old discarded couplers may be used where the rear portions of the shank are damaged, it being merely necessary to saw or cut off the damaged portion of the coupler shank and provide the same with a couple of bolt openings.

This emergency draft gear to be operative 80 in train line service, must have a perfectly workable coupling and uncoupling device. In case the end sill 37 or the end of the car is gone there is nothing to which the ordinary uncoupling levers and their brackets could be attached. Therefore, I have provided an angle plate 38, the lower arm 39 of which may be bolted into the pocket of the center beam 10 at the same time that the coupler is connected to the center beam, said angle plate being provided with an opening 39^a above the lock lifter 40, whereby a chain 41, one end of which is connected to the lifter 40, may pass through the opening 39^a in the angle plate and extend outwardly to the side of the car, where it may be suitably attached thereto. To uncouple the couplers, therefore, it is necessary only to pull on this chain 41.

By means of this emergency draft gear it 100 is a simple matter to temporarily repair damaged cars, the dimensions of which vary widely, and place the cars in such condition that the same may be used in regular train line service until the cars may be permanently repaired. These emergency draft 105 gears may be distributed along the road so that whenever the draft rigging of a car is damaged, one or more of these emergency draft gears may be quickly sent from a nearby point to the damaged car, whereupon the same may be repaired and put back into service with a loss of a minimum amount of time.

It is evident that there may be various 115 modifications of the invention as herein particularly shown and described, and it is my intention to cover all such modifications which do not depart from the spirit and scope of the invention as set forth in the 120 following claims.

I claim:

1. An emergency draft gear comprising a 125 coupler carrying member, a member supported by a car axle, and a height controlling member extending vertically between said other two members for supporting the coupler carrying member in position.

2. An emergency draft gear comprising a member for carrying a coupler, a member 130

connected thereto and resting upon a truck axle, and a yieldable member extending between said members for yieldably sustaining one of them.

3. An emergency draft gear comprising a member for carrying a coupler, a member connected thereto and supported by a truck axle, means associated with said members for varying the position of said coupler carrying member and including means for yieldably sustaining said coupler carrying member.

4. An emergency draft gear comprising a relatively fixed member, a member for carrying a coupler pivotally connected thereto, a supporting member which may rest upon a truck axle pivotally connected to said coupler carrying member, and a yieldable connecting member between said coupler carrying member and the member which is adapted to rest upon the truck axle.

5. An emergency draft gear comprising a member for carrying a coupler, a supporting member having a plurality of openings, and a member connecting said coupler carrying member and supporting member and having a plurality of openings by means of which the supporting member and connecting member may be selectively connected for varying the position of the coupler carrying member.

6. An emergency draft gear comprising a

member for carrying a coupler, a supporting member having a plurality of openings, a member connecting said coupler carrying member and supporting member and having a plurality of openings by means of which the supporting member and connecting member may be selectively connected for varying the position of the coupler carrying member, and means whereby there may be a yieldable movement between said coupler carrying member and supporting member.

7. An emergency draft gear comprising a member for carrying a coupler, a supporting member having a plurality of openings, a member connecting said coupler carrying member and supporting member and having a plurality of openings by means of which the supporting member and connecting member may be selectively connected for varying the position of the coupler carrying member, and yieldable means carried by said connecting member whereby there may be a yieldable movement between said coupler carrying member and supporting member.

Signed at Chicago, Illinois, this 26th day of December, A. D. 1917.

GEORGE G. FLOYD.
